UNITED STATES PATENT OFFICE.

WILLIAM O. BERRY, OF CARO, MICHIGAN.

CLEVIS.

1,330,836.

Specification of Letters Patent. Patented Feb. 17, 1920.

Application filed March 24, 1919. Serial No. 284,809.

To all whom it may concern:

Be it known that I, WILLIAM O. BERRY, a citizen of the United States of America, residing at Caro, in the county of Tuscola and

5 State of Michigan, have invented certain new and useful Improvements in Clevises, of which the following is a specification.

This invention relates to improvements in locking clevises and the like.

10 One object of the invention is to provide a clevis which will always be locked when in operative position.

Another object is to provide a simple, durable and inexpensive clevis from which the 15 pin member cannot be withdrawn until the clevis has been swung around the end of the doubletree and is in an inoperative position.

With the above and other objects in view, the present invention consists in the combination and arrangement of parts, herein-after more fully described, illustrated in the accompanying drawings, and more particularly pointed out in the appended claims, it being understood that changes may be made 25 in the form, size, proportion and minor details, without departing from the spirit or sacrificing any of the advantages of the invention.

In the drawing:—

30 Figure 1 is a fragmentary plan view of a common doubletree, showing my improved clevis in position.

Fig. 2 is also a plan view showing the clevis in inoperative position for unlocking.

35 Fig. 3 is a perspective view showing the clevis constructed in accordance with my invention, and

Fig. 4 is a side view of the pin locking member.

40 Referring now more particularly to the drawing, the numeral 1 indicates the commonly used doubletree which is usually pivoted in the center to the draft pole of a vehicle and which is provided at either end

45 thereof with suitable holes or opening 2, these holes are necessarily located near the back edge of the doubletree in order that the strength thereof may be retained.

The clevis member 3 is of the usual U-shaped formation with the arms 4 and 5 extending horizontally therefrom, each of the said arms being provided with an elongated slot 6, one end of which is enlarged and rounded to receive the locking pin member

55 8, which is cylindrical in form, and provided with a head to limit the downward move-

ment thereof when being placed in position in the clevis, and is of sufficient length to extend through and beyond the arm members 4 and 5.

60 By reference to Fig. 4 of the drawing, it will be noted that this pin member 8 is flattened on parallel sides thereof as shown at 9 and 9^a respectively and for a distance equal to the thickness of the said arm members, 65 in order that the said pin may readily slide in the slot formed in the said arms, and it will be readily understood that the diameter of the pin member 8 is greater than the width of the slot 6, excepting where it is 70 flattened to allow the said pin to slide therein, it will therefore be obvious that the shoulders formed by flattening the pin member in the places indicated will positively prevent the pin member from being 75 withdrawn until the clevis is swung around the end of the doubletree as shown by the numerous arrows in Fig. 2, and then forced to the position as shown in full lines, when the opening 7 will be in direct vertical 80 alinement with the opening 2 in the doubletree.

When using the ordinary clevis, it oftentimes happens that this pin member will gradually work up, due to rough roads or 85 by becoming caught on some portion of the vehicle box, and withdraw from the opening in the lower leg of the clevis, when this occurs the strain is of course obliquely across the upper part of the clevis and the clevis 90 will then either bend or break. With my improved construction it will be readily seen that this is impossible, inasmuch as it is necessary to swing the clevis around the end of the doubletree, and then force it forward 95 until the enlarged end of the slot registers with the opening 2 in the doubletree, this cannot happen when the clevis is in operative position on any vehicle as the draft is always forward, and the clevis could not 100 assume the positions necessary for unlocking without being manipulated by the operator.

105 From the foregoing description it will be obvious that I have perfected a simple and inexpensive locking clevis which is easy to manufacture and which will positively prevent the clevis from becoming disengaged or partly so when in operative position.

Claims:

110 1. A device of the character described including a whiffle tree having a bolt open-

ing made therein nearer the rear than the front edge, a clevis adapted to embrace the whiffle tree and having key-hole slots therein, and a bolt adapted to pass through the 5 registering enlarged portions of the key-hole slots and bolt opening in the whiffle tree and having reduced portions adapted to slidingly receive the restricted portions of the key-hole slots; the clevis adapted to be 10 slid on the bolt to bring the enlarged portions of the key-hole slots therein into registry with the bolt opening whereby the bolt may be withdrawn only when the clevis is rotated on the bolt out of the forward oper- 15 ative position, the forward edge of the whiffle tree adapted to engage the clevis and prevent sliding movement thereof on the bolt sufficient to bring the enlarged portions of the key-hole slots into registry with the 20 bolt opening when the clevis is in the forward operative position.

2. In combination with a whiffle tree having a vertically disposed bolt opening situated remote from the forward edge of the 25 whiffle tree as compared with the other edges thereof; a clevis composed of yoke arms fitting above and below the whiffle tree and having key-hole slots therein in vertical alignment, and a bolt of a diameter to pass 30 through the bolt opening and the enlarged rounded portions of the key-hole slots, said bolt also having flattened portions above and

below the whiffle tree for engaging in the restricted portions of the key-hole slots and shoulders adjacent the flattened portions for 35 engaging parts of the clevis to prevent withdrawal of the bolt except when the enlarged rounded portions of the key-hole slots align with the bolt opening, the remote position of the bolt opening from the forward edge 40 of the whiffle tree adapted to hold the clevis in such a way that the same will come into engagement with the forward edge of the whiffle tree before the enlarged rounded portions of the key-hole slots align with the bolt 45 opening, said clevis being rotatable on the bolt out of the forward position to permit such sliding thereof on the bolt as will bring the enlarged rounded portions of the key-hole slots into registry with the vertically 50 disposed opening.

3. A clevis, a bolt passing through the clevis and through a portion of the whiffle tree by which the clevis is supported remote from the forward edge thereof, said clevis being rotatable on the bolt and slideable thereon when in a rear position to permit withdrawal of the bolt, but the forward edge of the whiffle tree preventing such slideable movement of the clevis as will affect release of the bolt.

In testimony whereof I affix my signature.

WILLIAM O. BERRY.
